UNITED STATES PATENT OFFICE.

EDWIN OLDFIELD, OF NORWICH, CONNECTICUT.

WEFT STOP-MOTION FOR LOOMS.

SPECIFICATION forming part of Letters Patent No. 655,910, dated August 14, 1900.

Application filed February 16, 1898. Serial No. 670,599. (No model.)

To all whom it may concern:

Be it known that I, EDWIN OLDFIELD, a citizen of the United States, residing at Norwich, New London county, State of Connecticut, 5 have invented certain new and useful Improvements in Weft Stop-Motions for Looms, of which the following is a full, clear, and exact description.

This invention relates to narrow - fabric looms, and particularly to that class in which a multiple of shuttles is employed. My immediate purpose is to so improve such looms that the shuttle-quills shall be wound with the same length of filling-thread, and also to 15 provide a novel form of mechanism whereby the loom will be stopped at the exact instant that said quills are emptied.

By means of my new construction the loom runs continuously until such time as it becomes necessary to remove the emptied quills 20 from the entire series of shuttles and substitute full quills. The stopping of the loom is then performed positively and automatically and by means of very simple mechanism.

25 The quills are wound, as I have already stated, with a given length of filling and the loom is constructed to run just long enough to use said filling. As all the shuttles carry exactly the same length of filling, it will be 30 obvious that they will all be emptied simultaneously and also that with one stoppage of the loom all of said shuttles will be recharged with full quills, thus avoiding the careful watching of the loom now necessary and the 35 frequent stopping of said loom as the several quills are successively emptied of filling.

The drawings hereto illustrate my invention clearly.

Figure 1 is an end elevation of a part of a 40 loom-frame having mounted thereon those elements that are immediately related to my invention and therefore necessary to explain the same, and Fig. 2 is a front elevation of the same parts. Fig. 3 is an endwise view of 45 the batten and of certain of the elements of the stop-motion that are operated by said batten. Figs. 4 and 5 illustrate by side and sectional views portions of the time mechanism by means of which the loom is caused to 50 stop at the desired instant. Fig. 6 illustrates

a modification of the time mechanism of my invention.

In the drawings the letter *a* denotes the end frame of the loom; *b*, the breast-beam; *c*, the reciprocating-batten; *d*, the shuttle-race carried by said batten; *e*, a shuttle mounted in said "race," and *f* one of the pendent arms or so-called "swords," to the lower ends of which the batten *c* is secured. 55

The reference-letter *g* denotes the usual 60 longitudinally-movable shipper-rod, one end of which is connected with the belt or friction-clutch controlling the driving-shaft of the loom, such connection being of the ordinary character, and I have therefore thought it unnecessary to illustrate it. 65

Secured to one end of the shipper-rod *g* is a strap *g'*, that extends outward and downward over a roll *h*, mounted on the loom-frame, as seen in Figs. 1 and 2, the outer end of said 70 strap being secured to one arm of a bell-crank lever *i*, which is also pivoted on the frame *a*. The other (lower) arm of said bell-crank lever has pivoted thereto one end of a rod *k*, that extends horizontally toward the rear of the loom 75 a considerable distance, thence upward to form an offset or hook *k'*, and terminating in a horizontal portion *k''*, that is pivoted to a vertical connecting-rod *m*, whose upper end is pivoted to one arm of a bell-crank lever *n*, 80 mounted upon the loom-frame, as seen in Fig. 1.

The swinging batten *c* carries an arm *c'*, whose lower end is bent rearward to provide a hook *c''*. The offset or hook *k'*, which I have 85 described, lies normally below the level of the hook *c* and out of the arc-shaped path described by said hook when the loom is in operation and the batten is swinging back and forth; but under certain conditions, as I shall 90 explain presently, the hook *k'* is lifted into the path of hook *c''*, and as the batten continues its rearward movement the rod *k* is carried with it, thus rocking the angle-lever *i*, as seen in dotted lines in Fig. 3, and moving 95 the shipper-rod *g* endwise to shift the belt and stop the loom, as will be readily understood.

Projecting from the loom-frame *a* just above the crank-lever *n* is a threaded stud *o*, upon which is loosely mounted a threaded 100

roll o' , whose circumference is grooved or slightly reduced, as at o^2 , to receive a weighted cord p and whose inner end is enlarged to provide a disk o^3 , whose edge is cut with ratchet-teeth o^4 .

q indicates an arm having a hub q' , that is loosely mounted upon the stud o , the outer end of said arm being connected with one end of a rod s , whose other end bears an eccentric-strap s' , that is operated by an eccentric t on the main shaft a' of the loom in such manner as to give to the rod s an endwise-reciprocating movement at each revolution of the said shaft.

Pivoted to the arm q is a pawl q^2 , whose free end is held normally in engagement with the ratchet-teeth o^4 by a spring q^3 .

u denotes a detent or retaining pawl provided to prevent the backward rotation of the disk o^3 . Projecting from the outer face of said disk is a stud o^5 . The upper end of the crank-lever n extends upward to a point above the lowest position assumed by stud o^5 when the latter is carried around by disk o^3 , but when the roll o' is screwed home on the threaded stud o , as in full lines, Fig. 4, the stud o^5 may make several revolutions with disk o^3 without reaching the angle-lever n . Each revolution, however, of said roll o' causes it to be unscrewed on stud o , and as the roll is thus gradually moved outward the stud o^5 finally engages the angle-lever (see dotted lines, Fig. 4) and rocks said lever into the position shown by dotted lines in Fig. 1, thus raising the rod k and its offset k' into the path of the hook c^2 , which immediately engages said offset and causes the shipper-rod g to be moved to stop the loom. It should perhaps be stated that at each upward movement of the eccentric-rod s and arm q the pawl q^2 engages one of the ratchet-teeth o^4 and partially revolves the disk o^3 and roll o' , the disk and roll being held from following the pawl back by the detent u . As the roll o' is thus revolved, the cord p is gradually wound thereon and the weight elevated, as shown in dotted lines in Fig. 4. When the loom is ready to be started again, the pawl and detent are lifted by the operator out of engagement with the ratchet-teeth when the weight p' revolves the roll o' and causes it to travel on the threaded stud toward the loom-frame, thus carrying the stud o^5 away from the crank-lever n . It will now be understood that when the loom is started it will run until such time as the stud o^5 reaches and moves the crank-lever n and its connected parts, and that the length of time during which the loom is in operation will always be the same.

In Fig. 6 I have shown a modification of my invention in which the disk o^3 and threaded roll o' are held against rotation by a pawl u' , which at the proper time is raised by clock-work of any suitable form, such a clock being indicated in said Fig. 6 by reference-letter w . The clock is set to lift pawl u' after the loom has run a given length of time, and the

weighted cord p in seeking to descend rotates the roll o' to unscrew said roll outward, and thus carry the pin o^5 into engagement with the angle-lever n , when the latter is rocked (as already explained) to set in motion the belt-shipping devices. Having thus predetermined the length of time which the looms will run, I wind the quill in the shuttle e with a given length of filling-thread proportionate to such length of time and so that the filling-thread will be exhausted at precisely the instant that the loom stops.

If there are several shuttles, as in ribbon 80 and other narrow-fabric looms, I wind the quills of all the bobbins with exactly the same length of filling-thread, and as a result all the quills are simultaneously emptied and stopped. I am thus able to replenish the 85 shuttles with full quills at a single stopping of the loom instead of having to stop it from time to time as each one of the several shuttles is emptied, as is now necessary.

Inasmuch as my described improvement is 90 automatic in its action the operator is entirely relieved from the tiresome watching of the quills now necessary. A further and very valuable feature of my invention is in the quality of the weaving produced.

In this class of looms as commonly constructed failure to stop the loom before the filling-thread is run out makes it necessary to pick back and adjust the fabric before piecing in the new filling-thread, and this invariably leaves a noticeable defect in said fabric when the weaving is begun again. This very objectionable result is entirely overcome by my described improvement, as the loom is stopped positively and automatically just as the last end of the filling-thread is leaving the quill.

My improvement is of such a character that it may be easily attached to ordinary looms and is so simple that it may be operated by 110 any one intelligent enough to operate the loom proper.

Having thus described my invention, I claim—

1. In a loom, a supporting-stud, a laterally-moving disk placed thereon, and provided with a stud, and a mechanism for causing said disk or plate to revolve upon the stud for the purpose of stopping the loom, combined with means operated by said stud upon the disk or plate, the shipper-rod and mechanism for operating the shipper-rod, and a swinging batten which operates the mechanism connected with the shipper-rod when said mechanism is moved into the line of travel with said batten, substantially as shown.

2. In a loom, a supporting-stud, a disk which is movable laterally thereon, a mechanism for causing the disk to revolve, and move outwardly upon the stud, a mechanism for returning the disk to position on the stud, a suitable pawl for preventing the backward movement of the disk upon the stud, combined with means which are operated by said

disk, when the disk has reached the end of its travel for stopping the loom, mechanism for operating the shipper-rod, and which is moved into the line of travel with the batten 5 by the said means, the shipper-rod, and a swinging batten which operates the mechanism connected with the shipper-rod when the quills are empty, substantially as described.

3. A threaded stud, an operating disk or 10 plate placed thereon, and which has a lateral movement upon the stud, a mechanism for causing the disk to revolve, a pawl for preventing the backward movement of the disk, and a weighted cord attached to the disk for 15 causing it to return to position upon the stud, combined with means which is operated by the disk at predetermined times, a mechanism for operating the shipper-rod, and which is moved into the line of travel by said means,

20 the shipper-rod, and a swinging batten which operates the mechanism for operating the shipper-rod when the quills are empty, substantially as set forth.

4. In a loom, a threaded supporting-stud, 25 a revolving disk placed thereon and provided with an operating-stud upon its outer side, and which disk has a lateral movement upon the said stud, combined with an operating mechanism for causing the disk to revolve

30 forward, a pawl for preventing the disk from revolving backward, and a mechanism for causing the disk to return to position upon the stud when the pawl is raised, combined with suitable mechanism operated by said

35 disk at predetermined times, a shipper-rod connected to and operated by said mechanism, and a swinging batten which is brought into the line of travel with the batten, substantially as shown.

40 5. In a loom, the combination with a shipper-rod and batten, of stop mechanism operatively connected with said shipper-rod normally out of operative relation with said batten, a rotary member arranged to move

45 the stop mechanism into operative relation with the batten, and means for imparting a step-by-step movement to said rotary member.

6. In a loom, the combination with a batten and shipper-rod, of stop mechanism operatively connected with the shipper-rod and normally located out of the line of travel of the batten, actuating mechanism for moving said

stop mechanism into the line of travel of the batten and means for causing the operation of said actuating mechanism when the quills 55 are emptied.

7. In a loom, an operating-shaft, a rotary disk operated from said shaft, a stop mechanism, and a batten, combined with means whereby the disk is made to operate the stop 60 mechanism at predetermined times, whereby the machine is stopped at the same time that the thread is exhausted from all the bobbins, substantially as shown.

8. In a loom, the combination with the bat- 65 ten and shipper-rod, of stop mechanism operatively connected with the shipper-rod and normally out of operative relation with the batten, a rotary disk provided with a stud arranged to engage the stop mechanism and 70 to move it into operative relation with the batten, means for rotating said disk to cause the engagement of the stud with the stop mechanism, and means for returning the disk to its normal position. 75

9. In a loom, the combination with the bat- 80 ten and shipper-rod, of stop mechanism operatively connected with the shipper-rod and normally out of operative relation with the batten, a threaded stud, an interiorly-threaded 85 disk upon said stud and provided with a projection designed to engage the stop mechanism, means for imparting a step-by-step rotation to the disk, a pawl engaging the disk to prevent its backward rotation, and means for returning the disk to its normal position when the pawl is elevated.

10. In a loom, the combination with a bat- 90 ten and shipper-rod, of a bell-crank lever operatively connected with the shipper-rod, a swinging rod connected to said bell-crank lever and provided with a projection, a second bell-crank lever operatively connected with the swinging rod, and means for operating the second bell-crank lever at predetermined intervals to swing the projection 95 on the rod into the path of the batten.

Signed at Norwich, Connecticut, this 10th day of February, 1898.

EDWIN OLDFIELD.
